UNITED STATES PATENT OFFICE

2,072,923

TOOTHPICK DISPENSING APPARATUS

Walter Schutsch, New York, and George Kaeding,
Bronx, N. Y.

Application August 25, 1934, Serial No. 741,436

2 Claims. (Cl. 312—84)

This invention relates to new and useful improvements in tooth-pick dispensing devices, and it has for its object to provide an apparatus, which will place at the disposal of the party, desiring a tooth pick, only one tooth pick at the time, thus accomplishing the purpose of the said device in a strictly sanitary manner, contrary to the apparatus now commonly used, where a number of tooth picks may be ejected and left exposed to dust and other unsanitary conditions.

As the construction of our device is comparatively simple the cost of manufacturing should be proportionately low.

With the above and other objects in view, this invention consists of the novel features of construction, combination and arrangement of parts, hereinafter fully described, claimed and illustrated in the accompanying drawing forming part of this specification, and in which similar characters of reference indicate corresponding parts in all views, and in which:

Figure 1 is a front elevation of our invention.

Figure 2 is a transverse sectional view, taken on the line 2—2 in Figure 1.

Figure 3 is a side elevational view of our device, with a side part or section of the cover removed.

Figure 4 is a view of our device, partly in section, showing the mechanism in operation.

Referring more particularly to the drawing, 30 10 indicates a receptacle or casing, which is provided with a hinged lid 11, and has part of its front covered by a glass pane 12; said casing is formed with sidewise projections 13, adapted to have a drum member 14 turnably mounted 35 therein. The casing is further made with a slanting bottom 15, secured to the back of said casing by means of screws, as shown at 16, in Figure 2; the said bottom 15, which is formed with a slot 17 in its forward portion, extends only partly toward the front of the said casing, 40 the drum member 14 takes up the space between said bottom 15 and the front side of the casing.

At a distance below the bottom 15 and parallel with the latter a plate member 18 has been arranged in a downwardly slanting position, as shown especially in the Figures 2 and 4; said plate member which at one end has its downwardly bent flange secured to the back of the casing, as shown at 19, has its forward end portion or 50 extremity formed with a V-shaped catch, as shown at 20; the depth of said V-shaped terminal is, however, not greater than to permit only one tooth pick 39 at the time to be engaged and held thereby, whereas other or more tooth picks, if 55 expelled at the same time from the casing, will

roll over the one tooth pick, engaged by the V-shaped portion, and fall down in a box which is integrally attached to the casing 10 and serves as a reservoir 21 for the tooth picks, which may thus have been expelled in a superfluous manner.

The reservoir 21, which has the form of a substantially oblong casing, serves as a foot piece for the receptacle 10, to which it is integrally secured. The reservoir has at the upper portion of its front been formed with an opening 22 in its cover; the said cover may be secured in any suitable manner to the reservoir; the opening 22 is made to receive the superfluous tooth picks when these, as formerly explained, roll over the one caught by the V-shaped member, and in turn by means of an, as to distance, appropriately adjusted stop projection 23, are guided down in the reservoir.

The plate member 18, has upon its lower front surface been formed with a cut-out portion 24 as shown in Figure 1, to permit the easy removal 20 of the tooth pick from the V-shaped end portion of said plate.

The mechanism for expelling the tooth picks comprises a drum member 14, which by means of an axis 26 is turnably mounted in the forwardly 25 extending projections 13, 13 upon the casing, as shown in the Figures 1 and 3. The said drum is formed with a longitudinal recess 27 therein, as shown especially in Figure 5, said recess being adapted to have a tooth pick placed therein, as the latter is agitated or led into said recess by means of a ridged projection 28 formed upon said drum; the said projection 28 being made to slide in the slot 17 formed in the plate 15, when the drum is turned.

A lever 29 is made integral with a unit 30, which in turn is mounted upon one side of the drum, as shown especially in Figure 3. The said lever 29 is by means of a curved link 31 connected to an operable arm 32 terminating in a handle; said arm is in turn pivotally mounted upon the casing 10 by means of a screw bolt 33, while a spring 34 connected to a stud 35, and to said arm 32, as shown at 36, serves to actuate or bring back the drum member after the latter has been turned by means of the operable arm 32 in order to eject a tooth pick; a bolt or stop member, which has for its object to limit the movement of the arm 32, is shown at 37.

The casing 10 is at the front provided with a removable section 38, which normally covers the front of the drum member 14, but which may be removed in case any necessity therefore should arise.

Upon the side of the casing 10 is also remov-

35

ably arranged a small triangular shaped cover section 40, as may be seen in Figure 1; said cover section, which is secured in place by the studs or screws 35 and 37, serves to conceal and protect the actuating mechanism of the device.

It is obvious that changes may be made in the form, construction and arrangement of the several parts, as shown, within the scope of the appended claims, without departing from the spirit of the invention, and we do not therefore wish to limit ourselves to the construction and arrangement shown and described herein.

What we claim as new, and desire to secure by Letters Patent of the United States, is:—

15. 1. A tooth pick dispensing device, comprising, in combination, a casing for the placement of tooth picks therein, said casing being formed with a sidewise projecting section, a turnable drum member mounted partly in the casing and partly in said projecting section, and a removable panel covering the front of said section, the drum member having a recess formed at an obtuse angle therein to receive any shape of a tooth pick to be expelled, said drum member being 15 formed with a ridged portion for agitating the tooth picks, a slanting bottom arranged in the casing and adapted to co-operate with the drum member, a plate member arranged below said bottom and substantially parallel with the latter, 20 one end of said plate member being formed with a cut-out portion and terminating in a substantially V-shaped end portion adapted to receive and hold a tooth pick therein, the other end of said plate member being bent upon itself to form 25 a flange, whereby to attach said plate to the rear of the casing, a lever integral with a member mounted upon one side of the drum, a curved link connecting said lever to an operable arm terminating in a handle, said arm being pivotally 30 mounted upon the casing, a spring connected to a stud formed upon the casing and to said arm for actuating the drum member, a stop member arranged upon the casing for limiting the movement of said arm during operation, and a triangular shaped cover for concealing said mechanical parts.
20. 2. A tooth pick dispensing device, comprising, in combination, a casing for the placement of tooth picks therein, said casing being formed with a sidewise projecting section, a turnable drum member mounted partly in the casing and partly in said projecting section, and a removable panel covering the front of said section, the drum member having a recess formed at an obtuse angle therein to receive any shape of a tooth pick to be expelled, said drum member being 15 formed with a ridged portion for agitating the tooth picks, a slanting bottom arranged in the casing and adapted to co-operate with the drum member, a plate member arranged below said bottom and substantially parallel with the latter, 20 one end of said plate member terminating in a substantially V-shaped end portion adapted to receive and hold a tooth pick therein, the other end of said plate member being bent upon itself to form 25 a flange, whereby to attach said plate to the rear of the casing, a lever integral with a member mounted upon one side of the drum, a curved link connecting said lever to an operable arm terminating in a handle, said arm being pivotally 30 mounted upon the casing, a spring connected to a stud formed upon the casing and to said arm for actuating the drum member, a stop member arranged upon the casing for limiting the movement of said arm during operation, and a triangular shaped cover for concealing said mechanical parts.

spring connected to a stud formed upon the casing and to said arm for actuating the drum member, and a stop member arranged upon the casing for limiting the movement of said arm during operation.

2. A tooth pick dispensing device, comprising, in combination, a casing for the placement of tooth picks therein, said casing being formed with a sidewise projecting section, a turnable drum member mounted partly in the casing and partly in said projecting section, and a removable panel covering the front of said section, the drum member having a recess formed at an obtuse angle therein to receive any shape of a tooth pick to be expelled, said drum member being 15 formed with a ridged portion for agitating the tooth picks, a slanting bottom arranged in the casing and adapted to co-operate with the drum member, a plate member arranged below said bottom and substantially parallel with the latter, 20 one end of said plate member being formed with a cut-out portion and terminating in a substantially V-shaped end portion adapted to receive and hold a tooth pick therein, the other end of said plate member being bent upon itself to form 25 a flange, whereby to attach said plate to the rear of the casing, a lever integral with a member mounted upon one side of the drum, a curved link connecting said lever to an operable arm terminating in a handle, said arm being pivotally 30 mounted upon the casing, a spring connected to a stud formed upon the casing and to said arm for actuating the drum member, a stop member arranged upon the casing for limiting the movement of said arm during operation, and a triangular shaped cover for concealing said mechanical parts.
